FIG.3.

UNITED STATES PATENT OFFICE

2,185,466

UMBRELLA

Bernard J. Jostes, St. Louis, Mo.

Application June 5, 1939, Serial No. 277,349

4 Claims. (Cl. 135—22)

This invention relates to umbrellas, and with regard to certain more specific features, to self-opening umbrellas.

Among the several objects of the invention may be noted the provision of a self-opening umbrella of the class described which is so constructed as to increase substantially the life of the fabric covering of the umbrella; the provision of a self-opening umbrella wherein means are provided insuring against the undue straining of the fabric covering of the umbrella when the said umbrella is automatically opened; the provision of an umbrella of the class described which may be made quite compact in size relative to the area thereby covered, when it is opened; and the provision of an umbrella of the class described which is relatively simple and economical to construct. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a perspective view of an umbrella embodying the present invention;

Fig. 2 is a perspective view of a rib end, showing an alternative position in dotted lines; and,

Figures 3 and 4 are axial cross sections of certain umbrella opening mechanisms.

Similar reference characters indicate corresponding parts throughout the several views of the drawing.

Referring now more particularly to Fig. 1, numeral 1 indicates an umbrella stem, which is provided at its lower end with a suitable handle 2. Near the upper end of the stem 1 are radially pivoted the usual umbrella ribs 3, over which is stretched the customary fabric or other sheet-material covering 5.

Sliding on the stem 1 are a pair of telescoping cylinders 6 and 7 (see also Figures 3 and 4). The lower cylinder 6 has a portion 8 of reduced diameter at its lower end, which closely embraces the stem 1. The upper cylinder 7 has a closed upper end 9, which likewise closely embraces the stem 1. The cylinder 7 telescopes within the cylinder 6. Reacting between the opposite ends of cylinders 6 and 7 is a compression spring 10, which normally tends to force the two cylinders 6 and 7 out of telescoping arrangement. Prefer-

ably a collar 11 with a rubber washer 12 is secured to the stem 1 at a point near the upper end thereof, to prevent the cylinder 7 from coming entirely outside the cylinder 6, under the influence of the compression spring 10.

Around the upper end of the cylinders 7 are radially pivoted supporting ribs 13, which join to the main umbrella ribs 3, in a pivoted manner, at points substantially midway along the length of the said ribs 3. Around the upper edge of cylinder 6 are similarly pivoted, in radial manner, supporting ribs 14, the outer ends of which are pivoted each in one of ribs 13 a short distance from the outer ends of said ribs 13. The ribs 13 are preferably made channel-shape, while the ribs 14 may be of rectangular cross section.

The mechanism as above described, including the compression spring 10, and ribs 13 and 14, constitutes a self-opening type of umbrella that is not novel with the present applicant. It works in the following manner:

When the telescoping cylinders 6 and 7 are grasped in their Fig. 1 position, and drawn down towards the handle 2, the triangular relationship of each set of ribs 3, 13 and 14 is such that as the cylinders are brought closer to the handle 2, they are forced to telescope together, compressing the spring 10. At the same time, this operation folds the main umbrella ribs 3 down towards the stem 1, in the usual manner for closing an umbrella. Near the handle 2, the stem 1 is provided with a catch device 15, which is provided with a hook 16 that engages a slot 17 in the portion of restricted diameter 8 of cylinder 6. By means of the catch 15, the umbrella is held in closed position. However, if the umbrella is otherwise free of restraining influence, and the catch 15 is released, the compression spring 10, in expanding apart the telescoped cylinders 6 and 7, opens the umbrella to its fully opened, or Fig. 1 position.

As has been indicated, self-opening umbrellas of this general construction, have long been known. However, they have not come into widespread use, principally because of the following problem: When the umbrella is automatically opened by releasing the catch 15, it snaps to its open position with considerable force, as the release of the compression spring 10 cannot well be controlled to apply the force slowly. Consequently, each time a self-opening umbrella of this kind has been opened, the fabric covering has been subjected to relatively high peripheral stresses, because of the rapidly separating outer extremities of the ribs 3. With the fabrics avail-

able for umbrella covering, none of which are particularly strong, this has meant that the life of the covering of an umbrella of this type has been greatly shortened. In fact, in the past it has not been uncommon for the fabric coverings of self-opening umbrellas of this type to split or tear after no more than five or ten automatic openings. Consequent upon this problem, such automatic umbrellas have not come into widespread use, as no means has heretofore been found for solving this difficulty.

A principal object of the present invention is to solve the difficulty described above, and at the same time to obtain an umbrella which is more useful in several other respects than previous self-opening umbrellas.

The present invention solves the aforementioned difficulty in the following manner:

The main ribs 3 of the umbrella are usually made channel-shaped in cross section, for purposes of strength. This means that they will not undergo substantial bending from their initial curvature along their length. However, with the present invention, the outer extremities 20 of these main ribs 3 are flattened from their channel-shaped cross sections to provide relatively flat, flexible regions 18, as indicated in Fig. 2. The flat regions 18 preferably do not extend quite to the extreme tip of the ribs 3, but starts 25 immediately thereafter, and extend inwardly for a distance of, say, four or five inches towards the stem 1 of the umbrella.

These flat regions 18 are characterized by their resilient bendability, or flexibility, in a direction 30 in which the usual channel-shaped cross section of the rib prevents flexibility. They readily yield, for example, from the solid line position of Fig. 2, to the dotted line position therein.

When used in an umbrella with the self-opening mechanism heretofore described, the strains 40 upon rapid opening are taken up, not by the fabric covering 5, but by the flexing of the flat portions 18 of the ribs 3. This flexing occurs freely upon application of a force considerably 45 less than the force necessary to tear the covering material. Consequently, instead of opening in such a manner as to subject the covering material to a sudden tearing force, as was heretofore the case, the umbrellas of the present invention 50 open without subjecting the covering material to any substantial tearing force, since the flexible portions 18 of the main ribs 3 absorb the sudden force.

Such flexible-ended ribs 3 are not new per se 55 with the present applicant, but have long been used in the so-called "India-type" umbrellas. However, to the best of applicant's knowledge, such flexible-ended ribs have never heretofore been used in connection with a self-opening umbrella.

It is obvious that the principle of the present 60 invention applies not only to different types of self-opening mechanisms, all of which rely on a sudden-release-spring action for their opening

effects, but to other types of flexible-ribs as well. For example, instead of the patent portions 18, the ribs 3 may be terminated by sections of material flexible per se, such as whale bone or the like, and the advantageous effect of the present 5 invention thereby secured.

In view of the above, it will be seen that the several objects of the invention are achieved and other advantageous results attained.

As many changes could be made in the above 10 constructions without departing from the scope of the invention, it is intended that all matter contained in the above description or shown in the accompanying drawing shall be interpreted as illustrative and not in a limiting sense. 15

I claim:

1. In an umbrella, spring-operated self-opening means, and relatively flexible portions near the extremities of the umbrella ribs adapted to flex to protect the umbrella covering material 20 from the strain incident to the sudden action of the self-opening means.

2. An umbrella comprising a stem, radially pivoted ribs, covering material over said ribs, said ribs having relatively flexible regions near 25 their outer extremities, and spring-operated self-opening means sliding on said stem and cooperating with said ribs to open the umbrella automatically from its closed position, said flexible portions flexing on such automatic opening to 30 protect the umbrella covering material from the strains incident to the sudden action of the self-opening means.

3. An umbrella comprising a stem, radially pivoted ribs, covering material over said ribs, 35 said ribs having relatively flexible regions near their outer extremities, and spring-operated self-opening means sliding on said stem and cooperating with said ribs to open the umbrella automatically from its closed position, said flexible portions flexing on such automatic opening to 40 protect the umbrella covering material from the strains incident to the sudden action of the self-opening means, said ribs having channel-shaped cross sections for the majority of their length, with flattened regions providing the aforesaid 45 flexible portions.

4. An umbrella comprising a stem, radially pivoted ribs, covering material over said ribs, 50 said ribs having relatively flexible regions near their outer extremities, and spring-operated self-opening means sliding on said stem and cooperating with said ribs to open the umbrella automatically from its closed position, said flexible portions flexing on such automatic opening to 55 protect the umbrella covering material from the strains incident to the sudden action of the self-opening means, said self-opening means comprising two telescoping cylinders sliding on the aforesaid stem, a compression spring tending to force 60 said cylinders out of telescoping relation, and pivoted supporting ribs extending from each of said cylinders to and pivoted to said umbrella ribs.

BERNARD J. JOSTES.
